(21) Appl. No.: **29/109,062**

(57) **CLAIM**

(22) Filed: **Aug. 9, 1999**

The ornamental design for a halogen motion detection security light positioning system, as shown.

(51) LOC (7) Cl. **26-05**

DESCRIPTION

(52) U.S. Cl. **D26/63; D10/106**

FIG. 1 is a view in perspective as seen from the front left side of a halogen motion detection security light positioning system showing my new design;

(58) Field of Search D26/60-66; D10/106;

FIG. 2 is a top plan view;

362/267, 269, 271, 272, 273, 276, 282,

FIG. 3 is a front elevational view;

283, 285, 287, 418, 419, 42, 296, 297,

FIG. 4 is a right side view;

301, 306, 363, 384, 385; D13/139.2, 139.3

FIG. 5 is a left side view;

(56) **References Cited**

FIG. 6 is a rear elevational view; and,

U.S. PATENT DOCUMENTS

FIG. 7 is a bottom plan view.
